TELEGRAPH SYSTEM

Michael Idvorsky Pupin, deceased, late of Norfolk, Conn., by Varvara Pupin Smith, administratrix, Norfolk, Conn.

Application July 9, 1936, Serial No. 89,748

20 Claims. (Cl. 178—66)

This invention relates to telegraph communication systems and has for its principal object the provision of an improved system of long distance telegraphy.

5 The system may be employed in either land or submarine cable telegraphy, but is especially applicable to the latter because the problems and limitations involved therein are much more severe than in the former. It provides a more perfect 10 method of relaying than has heretofore been developed and makes more efficient use of the cable by increasing the signalling speed and reducing the time heretofore lost in synchronizing the various units. In addition, the equipment is greatly 15 simplified, thereby reducing the maintenance expense and the number of delays due to apparatus failures. The system as a whole is very reliable and comparatively simple to operate.

20 The system may also be employed in telegraphy by means of modulated high frequency waves. When used in wireless telegraphy it offers great advantages with regard to secrecy, and therefore is very desirable to both commercial companies and to military forces.

25 Broadly stated, the invention provides improved transmitting or sending apparatus for impressing on a cable or other communication channel, such as a submarine cable or overhead or conduit conductors in land telegraphy, signal pulses 30 having a definite, regular shape and uniform periodicity. An alternating synchronizing voltage is impressed on the same cable for the purpose of effecting synchronism between the sending and relaying units. Thus there is transmitted 35 over the cable or conductor a composite wave comprising the alternating synchronizing voltage with signal pulses superposed thereon.

40 When this wave arrives at the relaying station it is separated into its two components and the alternating voltage used to drive a synchronously operable relaying unit. This relaying unit functions to completely retransmit the received signal pulses, which are much distorted due to the attenuation characteristic of the cable, in their 45 original shape as sent out from the sending station.

45 As a primary aid in securing more perfect relaying, and in increasing the speed and reliability of the system as a whole, I provide a novel signal 50 reshaping or conforming unit. By means of this conforming unit it is possible to convert and translate a received signal wave of greatly distorted form into a series of signal pulses, each having a definite, precise shape and the succession of pulses having a uniform periodicity. The

proper functioning of this conforming unit depends upon only a portion of each received signal pulse and utilizes this portion to impress a constant voltage of corresponding polarity across a timing circuit. The portion of the signal pulse 5 so utilized is of definite duration and may be pre-selected to be the most characteristic portion of the pulse, that is, that portion having the maximum deviation from zero.

55 The timing circuit includes relay means actuated by the impressed voltage for repeating the impressed signal pulses in their conformed shape, and a time delay circuit for continuing the actuation of the relay means a predetermined length of time after the voltage is removed. The electromagnetic constants of the time delay circuit may be proportioned so as to give repeated signal pulses of the desired duration.

60 In order to select the desired portion of the received signal pulses, a contact maker is provided which makes a uniform, continuous series of contacts, with the interval between successive contacts equal to the interval between successive signal pulses, that is, the periodicity of the series of contacts is the same as that of the signal pulse 65 intervals. The duration of each contact is the same, and is equal to the predetermined fraction of the signal pulse which it is desired to utilize. This fraction may be chosen as desired, but a suitable value has been found to be one-fourth. 70 The contact maker operates jointly with relay means responsive to the received signals to impress the voltage across the timing circuit.

75 It will be apparent that the operation of the contact maker is such as to impress a constant voltage of definite duration across the timing circuit for each received signal pulse, and that the voltage will be impressed at uniform intervals equal to the interval between successive signal pulses. The magnitude and duration of this voltage 80 is independent of the received signal pulse, but the polarity is determined by the polarity of the selected portion of the signal. Therefore, the duration of successive contacts of the repeating relay means will be independent of the received signal pulses, but the sequence of contacts will depend upon the corresponding polarities of the received signal pulses. The repeating relays 85 may then be used to control the operation of apparatus for impressing corresponding signal 90 pulses on the cable.

95 Thus the relayed signal pulses will be of precise shape and uniform periodicity despite the severe distortion of the received signals occasioned by the attenuation characteristic of the 95

cable, which markedly increases with the frequency and therefore cuts off the higher harmonics in the signal wave.

Another advantage of this method of relaying is its inherent stability of operation in the presence of electrical disturbances on the cable, due to electrical storms, etc., and its comparative freedom from the effects of "zero wander". This is due to the fact that the correct functioning of the relaying unit depends only upon the portion of the signal pulse selected, and therefore it makes no difference what the shape of the incoming signal wave is, so long as the selected portions are of the correct polarity. Since these selected portions may be chosen from the most characteristic part of the signal pulse, a maximum deviation from the mean value of the signal train is permitted while still maintaining perfect relaying.

For the correct operation of the conforming unit it is necessary that the contact maker operate in synchronism with the received signal pulses, and therefore in synchronism with the sending unit. At the present time a well-known method of synchronization is the "clockhand" correction method. The units at the various stations are driven or controlled by phonic wheel motors, each motor energized with a direct current interrupted by a tuning fork. Since it is impossible to adjust the several tuning forks to vibrate in exact synchronism over an extended period of time, the fork at the transmitting station is adjusted to run either slightly faster or slightly slower than those at the other stations, and provision is made to restore periodically the units to exact synchronism. Thus continuous synchronism is not maintained but, instead, there is a periodic progressive departure therefrom, which may be undesirable when high signalling speeds are employed. Furthermore, this method of synchronization requires a tuning fork with associated corrective apparatus at each station, the frequency of which must be carefully adjusted, and therefore introduces apparatus which is expensive, may get out of order, and requires considerable time for correct synchronization after an idle period.

In the present system I provide apparatus for synchronization by means of a continuous alternating voltage sent over the same cable or communication channel as the message signals. This voltage is impressed on the cable by the transmitting unit, and the signal pulses superposed thereon. At the relaying station the synchronizing voltage is separated from the signal pulses by appropriate methods, preferably by a thermionic amplifier selectively tuned to the synchronizing frequency, and is used to control the operation of a phonic wheel motor.

The composite wave is also passed into another channel which contains a substantially distortionless amplifier. The synchronizing voltage may be eliminated from this channel by impressing thereon a voltage of like magnitude and frequency but of opposite phase, by means of a voltage generator similar to the one at the transmitting station, or by an appropriate voltage obtained from the synchronizing voltage amplifier.

The received signal pulses so separated are used to control the operation of the conforming unit in the manner hereinbefore described, and the contact maker of the unit is driven by the synchronously rotating phonic wheel motor. The phonic motor also drives the signal pulse generating equipment controlled by the conforming

unit, for impressing corresponding signals on the cable to the receiving station.

The conforming unit is also useful at the receiving station if it is desired to record signals by automatic printing equipment, and in that case a synchronizing voltage is sent over the cable from the relaying to the receiving station.

In a simplex system it is preferable to send out the synchronizing voltage from the signal transmitting station and relay the voltage to the receiving station, if desired, although it might be sent out from the relaying or receiving stations. In a duplex system the voltage may be impressed on the cable at either terminal station and relayed to the other terminal station. In either case all the synchronously operating units are controlled by means of a single unit at one of the stations and operate in synchronism therewith, so that only a single tuning fork is required for the entire system. For this reason it is not necessary to provide elaborate corrective apparatus to insure a constant frequency, such as is required when two or more forks vibrate at slightly different frequencies.

Thus this method of synchronization has many advantages over previous methods; it effects continuous synchronization of units separated by a long cable, instead of a periodic progressive departure therefrom; it permits controlling the units at the sending, relaying, and receiving stations by the use of only a single tuning fork, thereby eliminating apparatus which is expensive, may get out of order, and requires careful adjustment; and after the necessary adjustments are made at the time of installation no further adjustments are required for synchronizing the units after an idle period, thereby eliminating the time required for synchronization by present methods.

Since the signal pulses are impressed on the cable by the synchronously rotating apparatus, the frequency of the synchronizing voltage is always definitely related to the signalling speed. The term "signalling speed" is a convenient way to designate the rapidity with which successive signal pulses follow each other, and the phrase "frequency of the signal pulses" may be taken to mean the frequency of a continuous succession of signal pulses. It will be apparent that the signalling speed, or the frequency of the signal pulses, determines the speed with which any desired sequence of signal pulses may be transmitted. The relative frequencies and magnitudes of the synchronizing voltage and the signal pulses may be varied between wide limits but it has been found that a synchronizing voltage having one-fourth the frequency and one-third the magnitude of the signal pulses is very satisfactory, although magnitudes varying from one-tenth to one and one-half times the signal pulses have been employed with success.

As is well known, an inherent limitation on the speed of signalling is the attenuation characteristic of the cable, which markedly increases with frequency. Due to this discriminatory effect, signal pulses transmitted at too high a speed become practically indistinguishable, and are especially unsuited for automatic relaying. In order to enable the signals to be distinguishably received and therefore make possible a higher signalling speed, I preferably employ signal pulses consisting of a marking pulse of desired polarity followed by a curbing pulse of opposite polarity. The effect of this curbing is to define each marking pulse more clearly and definitely

so that in the received signal wave each pulse will appear as a decided hump. Advantage is taken of this in relaying by selecting the hump for the portion of the signal pulse which controls the conforming unit, thereby insuring reliability and accuracy of operation, and freedom from small disturbances. The employment of cabled signals also prevents charging the cable by a succession of like signal pulses, and so minimizes 10 zero wander effects.

As a further aid in improving the distinguishability of the signals, and the reliability and precision of operation, I employ the above-described conforming unit to control the signal pulse generating equipment at the transmitting station. A tape transmitter is used for converting spaced code punchings in a telegraphic tape into electric current pulses of corresponding polarity. It is evident that if there is any irregularity in the 20 size and spacing of the holes, or irregularity in the operation of the tape transmitter, these pulses will not be of desired uniformity. Therefore the conforming unit is employed to insure impressing on the cable signal pulses of definite, 25 precise shape and uniform periodicity. The use of the conforming unit in transmitting the signals is of course not necessary, and the tape transmitter may directly control the operation of signal impressing apparatus.

By using this conforming unit the tape transmitter may be of much simpler construction than that ordinarily used. It may consist merely of a drum of conducting material, over which the telegraphic tape passes, and a small contact element pressing lightly thereon, so that whenever a hole passes under the contact element an electric circuit, including a battery, will be closed. When used with the conforming unit this transmitter gives excellent results and possesses the great advantages of simplicity and reliability. The feeding of the tape, the operation of the conforming unit, and the operation of the signal pulse generating apparatus are all controlled by the phonic wheel motor at the transmitting station so that proper phase relations may be readily maintained.

The following is a detailed description of a preferred embodiment of my invention:

In the drawings, Fig. 1 is a schematic diagram showing the relationship between the various units at the sending, relaying, and receiving stations;

Fig. 2 shows a fragment of the telegraphic tape;

Fig. 3 is a side elevation of the tape transmitter;

Fig. 3a is an end elevation of the tape transmitter;

Fig. 4 is a diagram of the conforming unit;

Fig. 5 is a diagram of the apparatus for generating the message signal pulses and the synchronizing voltage, and impressing them on the cable;

Fig. 6 is a diagram showing a method of separating and amplifying the signal pulses and the synchronizing voltage at the relaying station;

Fig. 7 is a diagram to illustrate the advantages of using the conforming unit in relaying; and

Fig. 8 is a tabulation showing the wave forms found at various points in the system for a given sequence of dots and dashes.

Referring to Fig. 1, the various steps in the transmitting, relaying, and receiving of the message signals are shown in schematic form. For 75 purposes of clearness, all electric connections be-

tween units are shown by a single, heavy line, and the units themselves are shown as separate and distinct pieces of apparatus with their rotating elements coupled together, although in practice many of the units will be combined. In 5 the box representing each unit, the figure is indicated in which a more detailed showing of that unit may be found.

At the sending station the phonic motor drives the tape transmitter, which converts telegraphic 10 tape punchings into corresponding electric pulses; the conforming unit, which produces corresponding pulses of definite shape and uniform periodicity; a signal pulse controller and generator, controlled by these pulses and impressing 15 corresponding signal pulses on the cable; and a synchronizing voltage generator for impressing that voltage on the cable.

When the composite wave, comprising the signal pulses and the synchronizing voltage, reaches 20 the relaying station it passes into two amplifiers—the message channel amplifier, and the synchronizing channel amplifier. The latter is selectively tuned to the frequency of the synchronizing voltage and its output is used to control 25 the relaying phonic motor. This motor drives a synchronizing voltage eliminator which bucks out that voltage from the message channel, thereby leaving only the signal pulses, which are then fed into a conforming unit and completely re-shaped to their original form. These reshaped 30 pulses control a signal pulse controller and generator exactly as at the sending station, and impress corresponding signals on the succeeding cable section. The relaying phonic motor also drives a synchronizing voltage generator as at the 35 sending station.

At the receiving station the two components of the composite wave are separated as at the 40 relaying station, and a conforming unit reshapes the signal pulses for operating recording apparatus, such as an automatic printer. Of course, if a siphon recorder is used it will not be necessary to reshape the received signals and the synchronizing voltage need not be sent over the 45 cable to the receiving station, thereby eliminating the corresponding apparatus.

Fig. 2 shows a fragment of telegraphic tape 10 which may be used to transmit messages by the International Cable Code, in which a pulse of 50 current in one direction, say positive, signifies a dot, and a pulse of corresponding duration but of opposite polarity, a dash. The holes 11 represent dots and the holes 12 dashes. In order to feed the tape regularly and uniformly, a series 55 of holes 13 are provided.

Figs. 3 and 3a show a simple form of tape transmitter which may be employed. The phonic wheel motor 15 at the sending station has mounted on its shaft 16 a drum 17 of conducting material. The drum 17 has a row of projecting pins 18 around its circumference, which cooperate with holes 13 to feed the tape at the desired speed. Spring elements 20 are fastened to a suitable support 21 and carry at their lower ends 60 contact elements 22 and 23. These contact elements press lightly on the tape 10 and are so positioned that when holes 11 or 12 pass thereunder the inner contact elements pass through the holes and make contact with the drum 17, 65 thereby completing a suitable circuit and generating a corresponding pulse of current. Since it is customary to employ a tape which is waxed or paraffined, occasionally particles of wax are caught between the inner contact elements and 70 75

the drum, and prevent securing a good contact. For this reason the outer contact elements are provided, these elements engaging the portion of the drum outside the tape 10. The inner and outer contact elements are of the same length so that the outer element touches the drum when the corresponding inner element passes through a hole, thereby insuring a good electrical contact.

10 The circuits which are closed by the tape transmitter include the coils 19 and 19' (Fig. 4) of relays 24 and 24'. The connections are such that relay 24 is closed for a hole corresponding to a dot, and relay 24' for a hole corresponding to a dash. Sending phonic motor 15 has mounted on its shaft 16 the brushes 26 and 26' which are electrically connected together by sleeve 25, but insulated from the shaft. Brushes 26 and 26' make contact with conducting rings 27 and 27', respectively, which are preferably concentric, annular rings (here shown in developed form) mounted on a single face plate. Ring 27 is divided into twenty equal segments 28, which are separately insulated, and twenty equal segments 29, which are connected to conductor 31 as shown. Ring 27' is continuous and connected to a timing circuit 33 by conductor 32.

It is evident that if brushes 26 and 26' are rotated at a uniform speed, a uniform series of contacts will be made between conductors 31 and 32, all the contacts having the same duration. The conductor 31 is connected to the common point of two batteries 34 and 34', and the opposite ends of these batteries are connected to relays 24 and 24', respectively. The other terminals of the relays are connected together to the timing circuit 33 by conductor 35. Thus the timing circuit 33 is energized by the joint operation of relays 24, 24' and the contact maker 26-29.

The timing circuit 33 includes the repeating relays 36 and 36', shunted by a condenser 37 in series with resistance 38. Relays 36 and 36' are constructed so that current in one direction through the relays will close one but not the other, while current in the opposite direction will close the latter but not the former. Assume, that, at a certain instant, relay 24 is closed and brush 26 has just made contact with segment 29. Battery 34 will then energize the circuit and cause current to flow in the direction of arrow a. In the timing circuit, current will flow in the direction of arrow b, thus closing one of the relays, say relay 36, and will also charge the condenser 37 with the polarity indicated. Current in conductor 35 will continue to flow until brush 26 moves off segment 29, whereupon the circuit will be broken and condenser 37 will commence to discharge through relays 36 and 36'. Consideration will show that the discharge current will flow through the relays in the same direction as the previous current, that is, in the direction of arrow b. Therefore, relay 36 will remain closed until the magnitude of the discharge current falls below that necessary to continue actuation.

65 With a given voltage and duration of contact, the electromagnetic constants of the timing circuit may be determined so as to give the desired duration of actuation. For an example, assume the phonic motor speed to be two revolutions per second and segments 29 to be one-third the length of segments 28. Since there are twenty segments 29 in the ring, there will be forty contacts per second and each contact will have a duration of $\frac{1}{120}$ of a second.

For the purpose of mathematical analysis let:

E=voltage of battery 34

V=voltage across condenser 37 at time t

R₁=value of resistance 38

R₂=resistance of relays 36, 36' in series

L=inductance of relays 36, 36' in series

C=capacity of condenser 37

$$k = \frac{1}{R_1 C}$$

$$h = \frac{R_2}{L}$$

5

10

15

20

25

30

35

40

45

60

65

70

75

Then for any time t, measured from the beginning of the contact of brush 26 with segment 29, and assuming relay 34 closed: $V = E (1 - e^{-kt})$ by the well known calculation. If we assume $R_1 = 10^3$ ohms, and $C = 2 \times 10^{-6}$ farads, then $k = 500$ and $V = E$, very nearly, when $t = \frac{1}{4} \times 10^{-3}$, which is the duration of contact 26-29.

During this interval, current has been flowing through relays 36, 36' in the direction b according to the equation:

$$i_1 = \frac{E}{R_2} (1 - e^{-h_1 t})$$

If we assume $R_2 = 1.9 \times 10^4$ ohms and $L = 1$ henry, then $h = 1.9 \times 10^4$ and

$$i_1 = \frac{E}{R_2}$$

practically instantaneously, thus insuring the prompt closing of relay 36 as soon as brush 26 touches segment 29.

Now brush 26 moves off segment 29, thus breaking the circuit and permitting condenser 37 to discharge through the relays. This current is denoted by i_2 , and the value will be:

$$i_2 = \frac{E}{R_1 + R_2} (e^{-h_1 t} - e^{-h_2 t})$$

where

$$h_1 = \frac{R_1 + R_2}{2L} - \sqrt{\frac{(R_1 + R_2)^2}{4L^2} - \frac{1}{LC}}$$

$$h_2 = \frac{R_1 + R_2}{2L} + \sqrt{\frac{(R_1 + R_2)^2}{4L^2} - \frac{1}{LC}}$$

and t is measured from the instant the circuit is broken. The above-assigned values of R_1 , R_2 , L and C make the time constant h_2 very large compared to time constant h_1 , the value of which is 26. Therefore

$$i_2 = \frac{E}{R_1 + R_2} e^{-h_1 t}$$

very nearly. If we desire to maintain relay 36 in closed condition for the entire interval between successive contacts of the contact maker, then $t = \frac{1}{4} \times 10^{-3}$ and

$$i_2 = \frac{E}{2 \times 10^4} e^{-75/100}$$

Relays are available which keep their contacts closed with currents as small as 4 milliamperes, or less. Hence by making $E = 100$ volts the current at the end of $t = \frac{1}{4} \times 10^{-3}$ will be approximately 4 milliamperes, and relay 36 will remain closed for the entire $\frac{1}{40}$ of a second. It is apparent that the constants of the timing circuit may be adjusted so as to give any other desired duration of contact.

The purpose of the above-described conforming unit, at the sending station, is to produce pulses of definite shape and uniform periodicity from the pulses obtained from the tape transmitter. Therefore the contact maker should make a contact for each pulse from the tape

transmitter. With the above-assumed speed of the contact maker—forty contacts per second—the speed of feeding the tape and the spacing of the punched holes should be such as to give a signal pulse frequency of forty pulses per second. It is evident that the relays 36 and 36', actuated by the tape transmitter, need remain closed for only that portion of each pulse during which brush 46 passes over a segment 43, and that by adjusting the phase of brush 46 the middle portion of the pulse may be selected, thus permitting a considerable degree of irregularity in the spacing of the punched holes, while still maintaining the regularity of operation of the conforming unit.

The relays 36, 36', control the operation of the signal pulse generating equipment shown in Fig. 5. It will be assumed that relay 36 closes for a dot and 36' for a dash. Rings 46 and 46' are 5 conducting rings concentrically mounted on a face plate, preferably the same plate as rings 27, 27' of Fig. 4, and are connected to relays 36 and 36' respectively. Concentrically mounted therewith are segmented rings 43 and 43', each composed of twenty equal segments, 43 or 43', and twenty equal segments 44 or 44'. Segments 43 and 44' are connected together and to one side of battery 45, while segments 43' and 44 are connected together and to the opposite side of battery 45. Brushes 46, 46', 47 and 47' are mounted on the shaft 16 of phonic motor 18 and insulated therefrom. Brushes 46 and 46' are connected together, likewise 47 and 47', and each brush makes contact with the adjacent ring. These rings, with the contacting brushes, compose the signal pulse controller of Fig. 1.

The signal pulse generator 48 may be similar to the one shown in my U. S. Patent No. 1,657,587. It is a D. C. generator having two sets of field coils 49 and 50, which may be bifilarly wound. The coils are connected in series and across battery 45, and the sense of the windings is such that the current flowing through the two sets of coils in series produce equal and opposite magnetic fields. Thus by short-circuiting one or the other set of coils the field will be energized and a current will be induced in the armature, the latter being rotated at a uniform speed by a suitable motor (not shown). The rate of decay of current in the short-circuited coil affects the building up of the magnetic field, and so influences the shape of the output voltage wave. By adjusting the magnitudes of the resistances 51 and 51', this rate of decay may be determined so as to give the desired shape to the signal pulses. The common connection 52 of the two windings is connected to the common connection of relays 36 and 36'.

The E. M. F. induced in the armature of generator 48 is impressed on the cable 53 through a suitable shaping network 54. The cable may be operated either simplex or duplex, as desired, the connections for duplex operation being shown here. Since the proper method of duplexing is well known in the art, the receiving apparatus has been omitted from this diagram, for the sake of clearness.

The method of generating and impressing the message signals on the cable will now be described. As stated before, relays 36 and 36' are closed or opened according to the sequence of dots and dashes it is desired to transmit. Since the assumed phonic motor speed is two revolutions per second, and there are twenty pairs of segments 43, 44, the brush 46 will pass over the pairs of segments with the same periodicity as a contin-

uous succession of dots and dashes, and the time required to pass over each pair will be $\frac{1}{40}$ of a second.

Assume that it is desired to transmit a succession of dots, and that the constants of the timing circuit 33 are adjusted so that relay 36 remains closed $\frac{1}{40}$ of a second for each dot. The relay will thus remain closed continuously for a succession of dots. Now as soon as brush 47 touches segment 43' field coil 50 of generator 48 will be short-circuited, leaving field coil 49 to energize the field and impress a voltage of, say, positive polarity on the cable. As brush 47 moves off segment 43' and onto 44' the other field coil 49 will be short-circuited and coil 50 will now energize the field and impress a voltage of negative polarity on the cable.

Thus for each dot there will be impressed on the cable a signal pulse comprising a positive pulse, called the "marking" pulse, followed by a negative "curbing" pulse. It is found that a curbing pulse of the same magnitude and half the duration of the marking pulse gives excellent results. This means that segments 44, 44' should be half the length of segments 43, 43'. If a series of dashes is to be transmitted then relay 36' will be closed and whenever brush 46 is on a segment 43, field coil 49 will be short-circuited and when the brush is on a segment 44, field coil 50 will be short-circuited. Thus a series of dashes will consist of a series of negative marking pulses followed by shorter, positive, curbing pulses.

If a mixed series of dots and dashes is to be transmitted it is evident that the phase of the brushes should be adjusted so that the brush will start on a marking segment at the instant the corresponding relay 36 or 36' closes. This consideration determines the phase of brushes 46 and 47 with respect to brushes 26 and 26' of the molding unit.

The apparatus for impressing the alternating synchronizing voltage on the cable includes the concentric, conducting rings 55, 55' with corresponding contact brushes 56, 56' electrically connected together. Ring 55 is divided into ten equal segments, 57, 58, with segments 57 connected together and to one side of battery 45, and segments 58 to the opposite side. The primary windings 60, 60' of transformer 59 are also connected across the battery 45. The windings 60, 60' may be bifilarly wound and are of such sense that current flowing through the two in series will produce equal and opposite magnetic fields. The common point of the two windings is connected to ring 55'.

The operation of this synchronizing voltage generator is apparent. As brush 56 passes over segments 57, 58 it alternately short-circuits one or the other of the primary windings 60, 60', of transformer 59, thereby inducing a voltage in the secondary 61. The wave form of this induced voltage may be determined by regulating the rate of decay of current in the short-circuited coil with resistances 62, 62', as in the signal pulse generator. The secondary 61 is in series with the armature of generator 48 and the induced voltage is impressed on the cable along with the signal pulses. The frequency of the voltage, from the speed of the motor and the number of segments, will be ten cycles per second. Of course, it is possible to use a separate battery and impress the synchronizing voltage on the cable directly, instead of using transformer 59.

Referring now to Fig. 6, the composite wave composed of signal pulses and synchronizing voltage comes into the relaying unit at 63 through 75

an appropriate shaping network. Detailed description of the shaping network and the actual connections to the cable have been omitted, since they are well known in the art and form no part 5 of the present invention. For the same reason the thermionic amplifiers are indicated only dia-grammatically.

The received composite wave passes into a substantially distortionless message-channel amplifier 64, and also into a synchronizing channel amplifier 65. The latter includes a thermionic tube 66 in the plate circuit of which is a resonant circuit 67 comprising inductance 68 and capacitance 69, tuned to the frequency of the synchronizing voltage. This circuit presents a comparatively high external impedance to the synchronizing frequency but passes all others, so the voltage impressed on tube 70 is nearly all of synchronizing frequency. In order to increase the amplification, 10 if it is necessary, and further increase the selectivity of the amplifier, a coil 71 may be employed to feed back energy from the plate circuit into the grid circuit. Since the circuit 67 presents a comparatively low internal impedance to 15 the synchronizing frequency, a current of considerable magnitude may flow, thus greatly increasing the variation in the grid potential of tube 70.

In the plate circuit of tube 70 is also inserted 20 the actuating coil of relay 72, which therefore makes and breaks contacts 73 and 74 in accordance with the alternations of the synchronizing voltage. This energizes the field coil 75 of the 25 relaying phonic motor 76 by means of battery 77, and causes the motor to revolve in synchronism with the synchronizing voltage, in the well known manner.

The output of the message channel amplifier 30 64 contains the synchronizing voltage, and in order to eliminate this a voltage is induced in the 40 circuit by means of the synchronizing voltage eliminator 80. This eliminator may be constructed exactly like the synchronizing voltage generator shown in Fig. 5, numerals 55 to 62. By 45 properly designing the transformer 81 and adjusting the voltage of the battery 82 and the phase of the brushes 83, 83', it is possible to substantially eliminate the synchronizing voltage from the message channel, thereby leaving only 50 the signal pulses. The wave form of the eliminating voltage may be correctly shaped by the resistances 84, 84', as explained before, and if necessary a variable condenser 85, tuned to resonance, may be employed. It, of course, would 55 be possible to impress a voltage of suitable phase directly from the synchronizing channel amplifier, if so desired.

The signal wave is impressed on the grid of 60 thermionic tube 86 and the plate current actuates relays 87 and 87'. These relays are so adjusted that relay 87 closes for a positive signal pulse and 65 87' for a negative signal pulse. The relays correspond to relays 24 and 24' of Fig. 4 and control a conforming unit similar to that one.

The operation of the conforming unit is the same as before; it is controlled by only a portion 70 of each incoming signal pulse and the output is a series of corresponding signal pulses of definite, regular shape, and uniform periodicity. The output controls generating apparatus like that shown in Fig. 5, and therefore the signals impressed on the cable to the receiving station are exactly the same as those initially sent out by 75 the transmitting station. The synchronizing volt-

age may or may not be retransmitted, as pointed out previously.

An advantage of employing the conforming unit in relaying is shown in Fig. 7. The curve *m* represents the message signal pulses in the plate circuit of thermionic tube 86 (Fig. 6), and the zero line *o* is the value of current which flows when no signal is present. Relays 87 and 87' 10 are adjusted so that relay 87 closes whenever the current curve lies above the line *o*, while 87' 15 closes whenever the curve lies below that line. Now suppose the general level of current shifts to *o'*, due to zero wander, change in battery potentials, etc. It is evident, if the adjustment of the relays is not changed, that relay 87 will close 20 only during the portions *d*, of the current wave, while relay 87' will be closed the rest of the time. If relays 87, 87' were used to control the generating apparatus directly (i. e., were substituted for relays 36, 36' of Fig. 5) then the signals impressed 25 on the cable would not be of the correct shape at all, and would be unintelligible at the receiving station.

But suppose that the brushes of the conforming unit are set so that brush 28 passes over segment 25 29 during the interval *d*. Then the fact that the current curve drops below line *o* between successive contacts 28—29 will not effect the operation of the shaping unit or the relaying station generator.

Thus the general level of current through relays 87, 87' may vary through a much wider range if the conforming unit is employed than if it is omitted. In addition, of course, there is the advantage of providing perfectly definite 30 signal pulses, of correct shape, magnitude, and duration, despite any irregularities of disturbances present in the incoming wave.

Fig. 8 shows the types of waves which are found 35 at various points in the system. The sequence 40 of dots and dashes correspond to the tape punchings shown in Fig. 2. Curve *a* represents the duration of contact of relays 36, 36' in Figs. 4 and 5. Curve *b* shows each pulse of curve *a* broken up into a somewhat shorter marking pulse 45 followed by a curbing pulse of opposite polarity, by the signal pulse controller 46—46' of Fig. 5. Curve *c* shows the corresponding signals impressed on the cable by generator 48, the corners shown in curve *b* being rounded off due to the 50 time constants of the field coils 49, 50, etc. Curve *d* represents the synchronizing voltage impressed on the cable along with the signal pulses of curve *c*.

Curve *e* shows the received signal wave at the 55 relaying station after the synchronizing voltage has been removed. Curve *f* is similar but was obtained by earthing the cable after each marking pulse, instead of reversing the polarity. Note that the pulses are much more legible and pronounced in curve *e* than in curve *f*, thus illustrating the superiority of curbed sending.

Curve *g* represents the voltage impressed 60 across the timing circuit 33 (Fig. 4) of the conforming unit at the relaying station. The phase 65 of the brushes 26, 26' is such as to select the maximum values of the received signal pulses for the controlling portion. Curve *h* shows the short pulses lengthened by the timing circuit 33. Note that curve *h* is exactly the same as curve *a*, 70 but slightly displaced in phase.

In the preceding specification the construction and operation of the apparatus for the International Cable Code was described, but it is 75

apparent that the apparatus and system may be adapted to any code now in use.

It is also possible to adapt the method to systems of telegraphy by means of modulated high frequency currents sent over wires or through the air. Instead of directly impressing the composite wave, composed of signal pulses and synchronizing voltage, on the communication channel, the wave may be used to modulate a carrier wave, by methods well known in the art, and this modulated wave impressed on the communication channel. It will be understood that the term "communication channel" is intended to include not only a solid conductor, such as used in cable telegraphy or ordinary land telegraphy, but also any other medium suitable for carrying electric signalling currents, such as the atmosphere in wireless telegraphy. The modulated wave is demodulated at the relaying or receiving station and the resulting wave, which will be composed of signal pulses and synchronizing voltage, may be used to operate apparatus exactly as described above. The details of modulating, transmission, receiving, and demodulating are well known in the art and so are not given herein.

The advantages of my system as regards reliability and freedom from external disturbances are especially important in wireless telegraphy, because of static, etc. The use of the conforming unit in relaying is a primary aid in securing this reliability despite severe distortions of the signal wave, as pointed out in connection with Fig. 7.

Furthermore, the system offers a convenient, simple method of securing secrecy of transmission. This is due to the distorting of the train of signal pulses by the synchronizing voltage. By properly selecting the frequency, magnitude, and phase of this voltage the received composite wave may be made unintelligible except by properly eliminating the synchronizing voltage. In order for an outsider to decipher the message it would be necessary for him to discover the correct values of all three of the above quantities, and this would require considerable time as well as suitable equipment. If desired, it is also possible to vary the three quantities in accordance with a predetermined schedule, and thus make the outsider's task still more difficult. In wartime, when utmost secrecy is desirable, this method may be used to supplement the regular codes, and so further complicate and prolong any attempts on the part of the uninitiated to decipher the messages.

Claims:

1. In a telegraph system including synchronously operable sending and relaying units operatively connected by a communication channel, the method of signalling which comprises effecting continuous synchronization of the relaying and sending units by means of an alternating voltage impressed on said channel by the sending unit, superposing on said alternating voltage, the frequency of the signal pulse intervals bearing a definite ratio to that of the alternating voltage, controlling the operation of said relaying unit by the signals received during definite portions of the signal pulse intervals, and recreating signal pulses corresponding to those received during said intervals for retransmitting corresponding signals, the said recreated signal pulses having definite lengths substantially greater than the said portions of the signal pulse intervals.

2. In a submarine cable telegraph system including synchronously operable sending and re-

laying units operatively connected by a submarine cable, the method of signalling which comprises effecting continuous synchronization of the relaying and sending units by means of an alternating voltage impressed on said channel by the sending unit, superposing on said alternating voltage, the frequency of the signal pulse intervals bearing a definite ratio to that of the alternating voltage, controlling the operation of said relaying unit by the signals received during definite portions of the signal pulse intervals, and recreating signal pulses corresponding to those received during said intervals for transmitting corresponding signals the said recreated signal pulses having definite lengths substantially greater than the said portions of the signal pulse intervals.

3. In a telegraph system, a communication channel, a sending unit for impressing upon said channel an alternating synchronizing voltage and signal pulses superposed thereon, the frequency of the signal pulse intervals bearing a definite ratio to that of the synchronizing voltage, a synchronously operable relaying unit connected to said channel, means for causing said voltage to maintain said relaying unit in continuous synchronism therewith, and means for controlling the operation of said relaying unit by the signals received during definite portions of the signal pulse intervals, said relaying unit recreating signal pulses corresponding to those received during said intervals for retransmitting corresponding signals, the said recreated signal pulses having definite lengths substantially greater than the said portions of the signal pulse intervals.

4. In a telegraph system including terminal stations, a relaying station therebetween, and synchronously operable units at each station operatively connected by a communication channel, the method of signalling which comprises effecting continuous synchronization of said units by means of a continuous alternating voltage impressed on said channel by the unit at one of said stations, impressing signal pulses on said channel by means of the unit at one of said terminal stations, the frequency of the signal pulse intervals bearing a definite ratio to the frequency of said voltage, controlling the operation of the relaying unit by the signals received during definite portions of the signal pulse intervals, and recreating signal pulses corresponding to those received during said intervals for retransmitting corresponding signals to the other of said terminal stations, the said recreated signal pulses having definite lengths substantially greater than the said portions of the signal pulse intervals.

5. In a telegraph system including synchronously operable sending and receiving units operatively connected by a communication channel, the method of signalling which comprises effecting continuous synchronization of said units by means of a continuous alternating voltage impressed on said channel by one of said units, impressing signal pulses on said channel by means of said sending unit, the frequency of the signal pulse intervals bearing a definite relationship to the frequency of said voltage, controlling the operation of the receiving unit by the signals received during definite selected portions of the signal pulse intervals, and recreating signal pulses corresponding to those received during said intervals, the said recreated signal pulses having definite lengths substantially greater than the said portions of the signal pulse intervals.

6. In a telegraph system, a communication

channel, means for converting telegraphic tape punchings into corresponding electric pulses, a sending unit utilizing the portions of the pulses developed during definite portions of the signal pulse intervals to impress corresponding signal pulses on said channel, said sending unit also impressing on said channel a continuous alternating voltage having a frequency bearing a definite ratio to the frequency of the signal pulses, a synchronously operable relaying unit connected to said channel, means for causing said voltage to maintain said relaying unit in continuous synchronism therewith, and means for controlling the operation of said relaying unit by the signals received during definite portions of the signal pulse intervals, said relaying unit recreating signal pulses corresponding to those received during said intervals for retransmitting corresponding signals, the said recreated signal pulses having definite lengths substantially greater than the said portions of the signal pulse intervals.

7. In a telegraph system including a sending unit and a synchronously operable relaying unit operatively connected to a communication channel, the method of transmission which comprises impressing on said channel by said sending unit a continuous alternating voltage and signal pulses, the frequency of the signal pulses bearing a definite ratio to that of the alternating voltage, passing the impulses received at the other end of said communication channel into two channels, selectively amplifying the alternating voltage in one of said channels to the substantial exclusion of the signal pulses, utilizing said separated voltage to maintain the relaying unit in synchronism therewith, eliminating the alternating voltage in the other of said channels by an equal and opposite voltage impressed thereon by means of said separated voltage, and utilizing the signal pulses so separated to control the operation of the relaying unit for retransmitting corresponding signals.

8. In a telegraph system including a sending unit and a synchronously operable relaying unit operatively connected to a communication channel, the method of transmission which comprises impressing on said channel by said sending unit a continuous alternating voltage and signal pulses, the frequency of the signal pulses bearing a definite ratio to that of the alternating voltage, passing the impulses received at the other end of said communication channel into two channels, selectively amplifying the alternating voltage in one of said channels to the substantial exclusion of the signal pulses, utilizing said separated voltage to maintain the relaying unit in synchronism therewith, utilizing said synchronously operated unit to generate and impress a voltage in the other of said channels substantially equal and opposite to the alternating voltage contained therein, and utilizing the signal pulses so separated to control the operation of the relaying unit for retransmitting corresponding signals.

9. In a telegraph system including a sending unit and a synchronously operable relaying unit operatively connected to a communication channel, the method of transmission which comprises impressing on said channel by said sending unit a continuous alternating voltage and signal pulses, the frequency of the signal pulses bearing a definite ratio to that of the alternating voltage, passing the impulses received at the other end of said communication channel into two channels, selectively amplifying the alternating voltage in one of said channels to the substantial exclusion of the signal pulses, utilizing said separated voltage to

maintain the relaying unit in synchronism therewith, eliminating the alternating voltage in the other of said channels by an equal and opposite voltage impressed thereon by means of said separated voltage, and utilizing the portions of the signals received during only definite portions of the signal pulse intervals to control the operation of the relaying unit for retransmitting corresponding signals.

10. In a telegraph system including a sending unit and a synchronously operable relaying unit operatively connected to a communication channel, the method of transmission which comprises impressing on said channel by said sending unit a continuous alternating voltage and signal pulses, the frequency of the signal pulses bearing a definite ratio to that of the alternating voltage, passing the impulses received at the other end of said communication channel into two channels, selectively amplifying the alternating voltage in one of said channels to the substantial exclusion of the signal pulses, utilizing said separated voltage to maintain the relaying unit in synchronism therewith, utilizing said synchronously operated unit to generate and impress a voltage in the other of said channels substantially equal and opposite to the alternating voltage contained therein, and utilizing the portions of the signals received during only definite portions of the signal pulse intervals to control the operation of the relaying unit for retransmitting corresponding signals whose lengths are substantially greater than the said portions of the signal pulse intervals.

11. In a telegraph system, apparatus for reshaping signal pulses comprising relay means responsive to said signal pulses, contact means making a uniform series of contacts having the periodicity of a continuous succession of signal pulses, said contacts being of equal duration less than that of a signal pulse interval, an energizing circuit under joint control of said relay means and said contact means, a repeating relay having an actuating coil, said energizing circuit being adapted to energize said actuating coil when closed by the joint action of said relay means and said contact means, and means continuing actuation of said repeating relay for a preselected interval after said circuit is opened including a capacitance in parallel with said actuating coil, said capacitance being charged by the closing of said energizing circuit and discharging through the actuating coil after the energizing circuit is broken to continue the actuation of said repeating relay for said preselected interval.

12. In a telegraph system, apparatus for reshaping signal pulses comprising relay means responsive to said signal pulses, rotary contact means making a uniform series of contacts having the periodicity of a continuous succession of signal pulses, said contacts being of equal duration less than that of a signal pulse interval, an energizing circuit under joint control of said relay means and said contact means, repeating relay means having an actuating coil energized upon closure of said circuit, and capacitive means shunting the actuating coil of said repeating relay means, said capacitive means being charged by the closing of said energizing circuit and discharging through the actuating coil of said repeating relay after the energizing circuit is broken so as to continue actuation thereof for a preselected interval after said circuit is opened.

13. In a telegraph system, apparatus for reshaping signal pulses which comprises, a receiving relay responsive to said signal pulses, a con-

- 5 tact maker for making a uniform series of contacts having the periodicity of the signal pulse intervals, said contacts being of equal duration substantially less than that of a signal pulse interval, a repeating relay having an actuating coil, a capacitance in parallel with said actuating coil, the circuit including said capacitance and said actuating coil having resistance, inductance and capacitance, an energizing circuit including a 10 source of voltage under joint control of said receiving relay and said contact maker for applying said voltage to the first-mentioned circuit when the energizing circuit is closed by the closure of both receiving relay and contact maker and 15 thereby actuating said repeating relay and charging said capacitance, said voltage, resistance, inductance and capacitance being selected so that upon the opening of said energizing circuit the capacitance will discharge through the actuating 20 coil of the repeating relay and continue the actuation thereof for a selected interval thereafter, thereby generating repeated signals which persist for said selected interval.
14. In a telegraph system, a communication channel; a tape transmitter converting telegraphic tape punchings into corresponding electric signal pulses; and transmitting means controlled by means of only a portion of each of 25 said pulses to impress corresponding signals on said channel, said transmitting means comprising a relay selectively responsive to said signal pulses, a contact maker for making a uniform series of contacts having the periodicity of a continuous succession of signal pulses, said contacts being of equal duration substantially less than that of a signal pulse interval, an energizing circuit under joint control of said relay and said contact maker, a repeating relay having an actuating coil energized upon closure of said energizing circuit by the joint action of said relay and 30 said contact maker, a repeating relay having an actuating coil of said repeating relay after the energizing circuit is broken so as to continue actuation thereof for a selected interval after said circuit is broken, whereby signals which persist for said selected interval may be generated.
15. In a telegraph system including a communication channel, means for impressing upon said channel uniform signal pulses which comprises a feeding mechanism for feeding a tape perforated in accordance with the signal pulses which it is desired to transmit, a contact element positioned and constructed to continuously bear against a tape in said feeding mechanism, a relay controlled by said contact element so as to be actuated in accordance with the perforations in said tape 45 passing under said contact element, a contact maker correlated with said feeding mechanism for making a uniform series of contacts having the periodicity of the signal pulse intervals, said contacts being of equal duration substantially less than that of a signal pulse interval, an energizing circuit under joint control of said relay and said contact maker, a repeating relay having an actuating coil, said energizing circuit being adapted to energize said actuating coil when 50 closed by the joint action of said relay and said contact maker, and means continuing actuation of said repeater relay for a selected interval after said circuit is opened including a capacitance in parallel with said actuating coil, said capacitance 55 being charged by the closing of said energizing circuit and discharging through the actuating coil after the energizing circuit is broken to continue the actuation of said repeating relay for said selected interval.
16. In a telegraph system including a communication channel, means for impressing upon said channel uniform signal pulses which comprises a feeding mechanism for feeding a tape perforated in accordance with the signal pulses which it is desired to transmit, a contact element positioned and constructed to continuously bear against a tape in said feeding mechanism, a relay controlled by said contact element so as to be actuated in accordance with the perforations in said tape passing under said contact element, a contact maker correlated with said feeding mechanism for making a uniform series of contacts having the periodicity of the signal pulse intervals, said contacts being of equal duration substantially less than that of a signal pulse 60 interval, a repeating relay having an actuating coil, a capacitance in parallel with said actuating coil, the circuit including said capacitance and said actuating coil having resistance, inductance and capacitance, an energizing circuit including a source of voltage under joint control of the first-mentioned relay and said contact maker for applying said voltage to the first-mentioned circuit when the energizing circuit is closed by the closure of both the first-mentioned relay and 65 the contact maker and thereby actuating said repeating relay and charging said capacitance, said voltage, resistance, inductance and capacitance being selected so that upon the opening of said energizing circuit the capacitance will discharge through the actuating coil of the repeating relay and continue the actuation thereof for a selected interval thereafter, thereby generating repeated signals which persist for said selected interval.
17. In a telegraph system including a communication channel, in combination, means for impressing on said communication channel signal pulses and a continuous alternating synchronizing voltage, the frequency of said synchronizing voltage bearing a definite relationship to the frequency of the signal pulses, means for receiving said signal pulses and synchronizing voltage at the other end of said communication channel, means synchronized by the received synchronizing voltage for selecting definite portions of the signal pulse intervals, and means controlled by the signals received during the said selected portions for recreating corresponding signals of definite length substantially greater than the said selected portions of the signal pulse intervals.
18. In a submarine cable telegraph system, in combination, means for impressing on a submarine cable signal pulses and a continuous alternating synchronizing voltage, the frequency of said synchronizing voltage bearing a definite ratio to the frequency of the signal pulse intervals, means for receiving said signal pulses and synchronizing voltage at the other end of said cable, 70 a contact maker synchronized by the received synchronizing voltage for making a uniform series of contacts having the periodicity of the signal pulse intervals, the duration of said contacts being substantially shorter than said intervals, and a signal repeater under the joint control of the received signal pulses and said contact maker for recreating signals corresponding to the signal portions received while said contacts are made, the signals recreated by said signal re- 75

- peater having lengths substantially greater than the duration of said contacts.
19. In a submarine cable telegraph system, in combination, means for impressing on a submarine cable signal pulses and a continuous alternating synchronizing voltage, the frequency of said synchronizing voltage bearing a definite ratio to the frequency of the signal pulse intervals, means for receiving said signal pulses and synchronizing voltage at the other end of said cable, a receiving relay selectively responsive to the received and separated signal pulses, a contact maker synchronized by the received synchronizing voltage for making a uniform series of contacts having the periodicity of the signal pulse intervals, said contacts being of equal duration substantially less than that of a signal pulse interval, a repeating relay having an actuating coil, a capacitance in parallel with said actuating coil, the circuit including said capacitance and said actuating coil having resistance, inductance and capacitance, an energizing circuit including a source of voltage under joint control of said receiving relay and said contact maker for applying said voltage to the first-mentioned circuit when the energizing circuit is closed by the closure of both said receiving relay and the contact maker and thereby actuating said repeating relay and charging said capacitance, said voltage, resistance, inductance and capacitance being selected so that upon the opening of said energizing circuit the capacitance will discharge through the actuating coil of the repeating relay and continue the actuation thereof for a selected interval thereafter, thereby generating repeated signals persisting for said selected interval. 30
20. In a submarine cable telegraph system, in combination, means for impressing on a submarine cable signal pulses and a continuous alternating synchronizing voltage, the frequency of said synchronizing voltage bearing a definite ratio to the frequency of the signal pulse intervals, means for receiving said signal pulses and synchronizing voltage at the other end of said cable, a receiving relay selectively responsive to the received signal pulses, a contact maker synchronized by the received synchronizing voltage for making a uniform series of contacts having the periodicity of the signal pulse intervals, said contacts being of equal duration substantially shorter than said intervals, an energizing circuit under joint control of said receiving relay and said contact maker, a repeating relay having an actuating coil energized upon closure of said energizing circuit by the joint action of said receiving relay and said contact maker, and a capacitance in parallel with the actuating coil of said repeating relay, said capacitance being charged by the closing of said energizing circuit and discharging through the actuating coil of said repeating relay after the energizing circuit is broken so as to continue a tuation thereof for a selected interval after said circuit is broken. 25
21. In a submarine cable telegraph system, in combination, means for impressing on a submarine cable signal pulses and a continuous alternating synchronizing voltage, the frequency of said synchronizing voltage bearing a definite ratio to the frequency of the signal pulse intervals, means for receiving said signal pulses and synchronizing voltage at the other end of said cable, a receiving relay selectively responsive to the received signal pulses, a contact maker synchronized by the received synchronizing voltage for making a uniform series of contacts having the periodicity of the signal pulse intervals, said contacts being of equal duration substantially shorter than said intervals, an energizing circuit under joint control of said receiving relay and said contact maker, a repeating relay having an actuating coil energized upon closure of said energizing circuit by the joint action of said receiving relay and said contact maker, and a capacitance in parallel with the actuating coil of said repeating relay, said capacitance being charged by the closing of said energizing circuit and discharging through the actuating coil of said repeating relay after the energizing circuit is broken so as to continue a tuation thereof for a selected interval after said circuit is broken. 30

22. In a submarine cable telegraph system, in combination, means for impressing on a submarine cable signal pulses and a continuous alternating synchronizing voltage, the frequency of said synchronizing voltage bearing a definite ratio to the frequency of the signal pulse intervals, means for receiving said signal pulses and synchronizing voltage at the other end of said cable, a receiving relay selectively responsive to the received signal pulses, a contact maker synchronized by the received synchronizing voltage for making a uniform series of contacts having the periodicity of the signal pulse intervals, said contacts being of equal duration substantially shorter than said intervals, an energizing circuit under joint control of said receiving relay and said contact maker, a repeating relay having an actuating coil energized upon closure of said energizing circuit by the joint action of said receiving relay and said contact maker, and a capacitance in parallel with the actuating coil of said repeating relay, said capacitance being charged by the closing of said energizing circuit and discharging through the actuating coil of said repeating relay after the energizing circuit is broken so as to continue a tuation thereof for a selected interval after said circuit is broken.

ratio to the frequency of the signal pulse intervals, means for receiving and separating said signal pulses and synchronizing voltage at the other end of said cable, a receiving relay selectively responsive to the received and separated signal pulses, a contact maker synchronized by the received and separated synchronizing voltage for making a uniform series of contacts having the periodicity of the signal pulse intervals, said contacts being of equal duration substantially less than that of a signal pulse interval, a repeating relay having an actuating coil, a capacitance in parallel with said actuating coil, the circuit including said capacitance and said actuating coil having resistance, inductance and capacitance, an energizing circuit including a source of voltage under joint control of said receiving relay and said contact maker for applying said voltage to the first-mentioned circuit when the energizing circuit is closed by the closure of both said receiving relay and the contact maker and thereby actuating said repeating relay and charging said capacitance, said voltage, resistance, inductance and capacitance being selected so that upon the opening of said energizing circuit the capacitance will discharge through the actuating coil of the repeating relay and continue the actuation thereof for a selected interval thereafter, thereby generating repeated signals persisting for said selected interval. 30

- peater having lengths substantially greater than the duration of said contacts.
19. In a submarine cable telegraph system, in combination, means for impressing on a submarine cable signal pulses and a continuous alternating synchronizing voltage, the frequency of said synchronizing voltage bearing a definite ratio to the frequency of the signal pulse intervals, means for receiving said signal pulses and synchronizing voltage at the other end of said cable, a receiving relay selectively responsive to the received and separated signal pulses, a contact maker synchronized by the received synchronizing voltage for making a uniform series of contacts having the periodicity of the signal pulse intervals, said contacts being of equal duration substantially less than that of a signal pulse interval, a repeating relay having an actuating coil, a capacitance in parallel with said actuating coil, the circuit including said capacitance and said actuating coil having resistance, inductance and capacitance, an energizing circuit including a source of voltage under joint control of said receiving relay and said contact maker for applying said voltage to the first-mentioned circuit when the energizing circuit is closed by the closure of both said receiving relay and the contact maker and thereby actuating said repeating relay and charging said capacitance, said voltage, resistance, inductance and capacitance being selected so that upon the opening of said energizing circuit the capacitance will discharge through the actuating coil of the repeating relay and continue the actuation thereof for a selected interval thereafter, thereby generating repeated signals persisting for said selected interval. 30
20. In a submarine cable telegraph system, in combination, means for impressing on a submarine cable signal pulses and a continuous alternating synchronizing voltage, the frequency of said synchronizing voltage bearing a definite ratio to the frequency of the signal pulse intervals, means for receiving said signal pulses and synchronizing voltage at the other end of said cable, a receiving relay selectively responsive to the received signal pulses, a contact maker synchronized by the received synchronizing voltage for making a uniform series of contacts having the periodicity of the signal pulse intervals, said contacts being of equal duration substantially shorter than said intervals, an energizing circuit under joint control of said receiving relay and said contact maker, a repeating relay having an actuating coil energized upon closure of said energizing circuit by the joint action of said receiving relay and said contact maker, and a capacitance in parallel with the actuating coil of said repeating relay, said capacitance being charged by the closing of said energizing circuit and discharging through the actuating coil of said repeating relay after the energizing circuit is broken so as to continue a tuation thereof for a selected interval after said circuit is broken. 25
21. In a submarine cable telegraph system, in combination, means for impressing on a submarine cable signal pulses and a continuous alternating synchronizing voltage, the frequency of said synchronizing voltage bearing a definite ratio to the frequency of the signal pulse intervals, means for receiving said signal pulses and synchronizing voltage at the other end of said cable, a receiving relay selectively responsive to the received signal pulses, a contact maker synchronized by the received synchronizing voltage for making a uniform series of contacts having the periodicity of the signal pulse intervals, said contacts being of equal duration substantially shorter than said intervals, an energizing circuit under joint control of said receiving relay and said contact maker, a repeating relay having an actuating coil energized upon closure of said energizing circuit by the joint action of said receiving relay and said contact maker, and a capacitance in parallel with the actuating coil of said repeating relay, said capacitance being charged by the closing of said energizing circuit and discharging through the actuating coil of said repeating relay after the energizing circuit is broken so as to continue a tuation thereof for a selected interval after said circuit is broken. 30
22. In a submarine cable telegraph system, in combination, means for impressing on a submarine cable signal pulses and a continuous alternating synchronizing voltage, the frequency of said synchronizing voltage bearing a definite ratio to the frequency of the signal pulse intervals, means for receiving said signal pulses and synchronizing voltage at the other end of said cable, a receiving relay selectively responsive to the received signal pulses, a contact maker synchronized by the received synchronizing voltage for making a uniform series of contacts having the periodicity of the signal pulse intervals, said contacts being of equal duration substantially shorter than said intervals, an energizing circuit under joint control of said receiving relay and said contact maker, a repeating relay having an actuating coil energized upon closure of said energizing circuit by the joint action of said receiving relay and said contact maker, and a capacitance in parallel with the actuating coil of said repeating relay, said capacitance being charged by the closing of said energizing circuit and discharging through the actuating coil of said repeating relay after the energizing circuit is broken so as to continue a tuation thereof for a selected interval after said circuit is broken. 35
